DESIGN FOR A WATER CLOSET

Clarence Karstadt, Detroit, Mich., assignor to Briggs Manufacturing Company, Detroit, Mich.,
a corporation of Michigan

Application August 27, 1936, Serial No. 64,598

Term of patent 3½ years

To all whom it may concern:

Be it known that I, Clarence Karstadt, a citizen of the United States, residing at Detroit, county of Wayne, State of Michigan, have invented a new, original, and ornamental Design for a Water Closet, of which the following is a specification, reference being had therein to the accompanying drawing, forming a part thereof, in which

Fig. 1 is a perspective view of the water closet;
and

Fig. 2 is a side elevation thereof.

I claim:

The ornamental design for a water closet, substantially as shown.

CLARENCE KARSTADT.
